DESIGN FOR A LAMP OR SIMILAR ARTICLE

Corinne Holt Gould, Portland, Oreg.

Application September 10, 1941, Serial No. 103,283

Term of patent 3½ years

To all whom it may concern:

Be it known that I, Corinne Holt Gould, a citizen of the United States, residing at Portland, in the county of Multnomah and State of Oregon, have invented a new, original, and ornamental Design for a Lamp or Similar Article, of which the following is a specification, reference being had to the accompanying drawing, forming part thereof.

I claim:

The ornamental design for a lamp or similar article, substantially as shown.

CORINNE HOLT GOULD.
